(57) **CLAIM**

I claim an ornamental design for a heat reflective lining material, as shown and described.

DESCRIPTION

FIG. 1 is a front view of the heat reflective lining material, showing my new design;

FIG. 2 is a side view thereof;

FIG. 3 is a back view thereof;

FIG. 4 is a perspective view thereof;

FIG. 5 is a perspective view of the heat reflective lining material of FIG. 1 shown in a position of use;

FIG. 6 is a perspective view of the heat reflective lining material of FIG. 1 shown in a second position of use; and,

FIG. 7 is a perspective view of the heat reflective lining material of FIG. 1 shown in a third position of use.

The broken line perimeter in the drawings represents the boundary of the claimed design and forms no part thereof. The broken lines in FIGS. 5, 6 and 7 represent environmental structure and form no part of the claimed design.

1 Claim, 5 Drawing Sheets
